(57) **CLAIM**

The ornamental design for a magnetic device mount, as shown and described.

DESCRIPTION

FIG. 1 is a front perspective view showing a magnetic device mount;

FIG. 2 is a rear perspective view thereof;

FIG. 3 is a top plan view thereof;

FIG. 4 is a front elevation view thereof;

FIG. 5 is a right side elevation view thereof;

FIG. 6 is a left side elevation view thereof;

FIG. 7 is a rear elevation view thereof; and,

FIG. 8 is a bottom plan view thereof.

In the drawings, the broken line showings are for the purpose of illustrating portions of the magnetic device mount that form no part of the claimed design.

Unshaded surfaces adjacent to broken lines form no part of the claimed design.

1 Claim, 3 Drawing Sheets
